UNITED STATES PATENT OFFICE

92,139

DESIGN FOR A CARTON

Garland Waddy Wilde, Richmond, Va.

Application February 21, 1934, Serial No. 50,824

Term of patent 7 years

To all whom it may concern:

Be it known that I, GARLAND WADDY WILDE, a citizen of the United States, residing at Richmond, in the State of Virginia, have invented a new, original, and ornamental Design for a Carton, as shown in the accompanying drawing and described in the following specification.

In the drawing the sole figure is a perspective view of a carton showing my new design.

The carton is of that type adapted to contain a pack of collection envelopes bearing a serial number, which number is visible through an

opening A in the carton. The ornamental design applied to the surface of the carton is in simulation of a two-volume book having superposed book marks simulating ribbons, appearing to emanate between pages at the top of one of the volumes and overlappingly arranged to form a narrow panel, having the opening A near the top.

I claim:

The ornamental design for a carton as shown and described.

GARLAND WADDY WILDE.
